UNITED STATES PATENT OFFICE.

ALBEN E. LUNDELL, OF NEW YORK, N. Y., AND FRANKLIN A. STEARN, OF PATERSON, NEW JERSEY, ASSIGNEES TO WESTERN ELECTRIC COMPANY, INCORPORATED, OF NEW YORK, N. Y., A CORPORATION OF NEW YORK.

TELEPHONE-EXCHANGE SYSTEM.

1,257,370.

Specification of Letters Patent. Patented Feb. 26, 1918.

Application filed October 26, 1916. Serial No. 127,934.

To all whom it may concern:

Be it known that we, ALBEN E. LUNDELL and FRANKLIN A. STEARN, citizens of the United States, residing at New York, in 5 the county of Bronx and State of New York, and at Paterson, in the county of Passaic and State of New Jersey, respectively, have invented certain new and useful Improvements in Telephone-Exchange Systems, of which the following is a full, clear, 10 concise, and exact description.

This invention relates to telephone exchange systems.

The object of this invention is to provide 15 means whereby a connecting operator is informed, by means of a tone in the receiver of her head set, that a calling subscriber desires her attention after a connection has been set up.

20 A feature of this invention is a relay arrangement by which such tone is connected to the operator's receiver for a predetermined length of time.

The drawing shows portions of a circuit 25 arrangement suitable for carrying out the invention.

It is thought the invention will best be understood from the following detailed description, reference being had to the accompanying drawing.

The invention is shown as applied to a semi-automatic telephone exchange system of the type disclosed in an application by A. E. Lundell, Serial No. 70,459, filed January 5, 1915, only so much of this system being shown as is necessary to an understanding of the present invention. The invention is not restricted to this particular system, since it is obviously capable of arrangement for use with other systems.

40 When the subscriber at substation 1 desires a connection he removes his receiver from the hook, whereupon a line relay 2 is energized to cause the display of a line signal 3 in the well-known manner.

An operator, one of whose cord circuits is indicated at O, upon observing the lighting of signal 3, inserts a plug 4 into a jack 5 associated with line signal 3. A circuit 50 is then closed for answering supervisory relay 6 in the well-known manner. At the same time a cut-off relay 7 and a sleeve relay 8 are energized over the sleeve contacts of plug 4 and jack 5.

Relay 8, upon energization, completes a 55 circuit from grounded battery, power magnet of listening key sequence switch 20, outer armature and front contact of relay 8 to ground for moving this sequence switch out of position 1 and into position 7. 60

When the listening key sequence switch, certain contacts of which are indicated at 17, 18 and 19, arrives in position 7, a circuit is closed to the operator's head set through sequence switch contacts 18, 19, and she may 65 then converse with the calling subscriber and learn the number of the wanted line. She then sets up the desired connection as disclosed in the above mentioned application, the arrangement indicated in the drawing showing brushes 9 and 10 of an automatic switch by which such connection may be advanced.

If, after the listening key sequence switch has left its listening-in position, the calling 75 subscriber desires to attract the attention of the operator, he replaces his receiver on the hook for an instant and then again removes it. When the receiver is replaced on the hook, the supervisory relay 6 is deenergized 80 and completes a circuit from grounded battery, left-hand winding of relay 11, armature and back contact of relay 6, lamp 12, to ground at the inner armature and front contact of relay 8. Relay 11 is energized 85 and completes a locking circuit for itself from grounded battery, right-hand winding of relay 11, its right-hand armature and front contact, listening key sequence switch contact 17, closed in positions 8 to 18, to 90 ground at the armature and back contact of slow release relay 13.

When the receiver is again removed from the hook supervisory relay 6 is again energized, and slow release relay 14 is energized over a circuit from 95 grounded battery, right-hand winding of relay 14, left-hand armature and front contact of relay 11, armature and front contact of relay 6, lamp 12, to ground at the armature and front contact of relay 8. Relay 14 100 attracts its armatures and completes a circuit by which a tone is induced into the operator's receiver, such circuit being from grounded battery, interrupter 15, primary winding of coil 16, to ground at the right-hand armature and front contact of relay 14. Relay 14 at its left-hand armature completes a circuit from grounded battery, left-

hand armature and front contact of relay 14, winding of relay 13 and left-hand winding of relay 14, to ground. Relay 13 attracts its armatures and at its left-hand armature opens the locking circuit of relay 11, which deenergizes, thereby opening the circuit through the right-hand winding of relay 14. In addition, relay 13 at its left-hand armature shunts out the left-hand winding of relay 14, the energizing circuit of relay 13 now being from grounded battery, left-hand armature and front contact of relay 14, winding of relay 13, to ground at the left-hand armature and front contact. The circuits of both windings of relay 14 are now open and after a time it releases its armatures. When the left-hand armature of relay 14 is retracted, the energizing circuit of relay 13 is broken and after a time it retracts its armatures, breaking at its right-hand armature the circuit over which the tone was produced in the operator's head set. It will be noted that the tone will begin when relay 14 is energized and continues until relay 13 is deenergized. The relays are now all in the condition in which they were when the connection was first established.

The supervisory lamp 12 is lighted during the time in which relay 11 is energized and aids the operator in determining which subscriber desires her attention.

At conclusion of conversation, the calling subscriber replaces his receiver and causes the permanent deenergization of relay 6. Supervisory lamp 12 is lighted over a circuit from grounded battery, left-hand winding of relay 11, armature and back contact of relay 6, lamp 12, and inner armature and front contact of relay 8, to ground. Relay 11 is energized but relay 14 does not energize since relay 6 is not again energized. When the operator removes the plug 4 from the jack 5, relay 8 is deenergized and the supervisory lamp 12 is extinguished.

What is claimed is:

1. In a telephone exchange system, calling and called lines, an operator's circuit for interconnecting said lines, an operator's receiver, means for connecting said operator's receiver to a calling line, means to audibly inform said operator that the calling subscriber desires her attention after a connection has been established, and means for applying said informing means for a predetermined length of time.

2. In a telephone exchange system, calling and called lines, an operator's circuit for interconnecting said lines including a plurality of relays, an operator's receiver,

means for audibly informing said operator that a calling subscriber desires her attention after a connection has been established, the duration of application of said informing means being dependent on the time required for the release of certain of said relays.

3. In a telephone exchange system, calling and called lines, an operator's circuit for interconnecting said lines including an answering supervisory relay, a combination of relays, an operator's receiver, means for connecting said operator's receiver with a calling line, means to audibly inform said operator that a calling subscriber desires her attention after a connection has been established, a circuit arrangement for successively energizing said combination of relays upon the deenergization of said supervisory relay, means for causing the successive deenergization of said combination of relays upon reenergization of said supervisory relay, said informing means being applied to said operator's receiver during the actuation and release of said combination of relays.

4. In a telephone exchange system, calling and called lines, an operator's circuit for interconnecting said lines, an operator's receiver, means for connecting said operator's receiver to a calling line, means to audibly inform said operator that a calling subscriber desires her attention after a connection has been established, and means for preventing the application of said audible informing means when said operator first establishes a connection to a called line.

5. In a telephone exchange system, calling and called lines, an operator's circuit for interconnecting said lines including an answering supervisory relay, an operator's receiver, a relay arranged to be energized in certain stages of operation of said system upon the deenergization of said supervisory relay, a pair of slow-release relays, means to cause current variations in said receiver to produce a tone audible to said operator, the application of said means being controlled at a front contact of either of said slow-release relays, means for successively energizing said slow-release relays, and means controlled by the interaction of said relays for restoring all of said relays to a normal condition.

In witness whereof, we hereunto subscribe our names this 25th day of October, A. D. 1916.

ALBEN E. LUNDELL
FRANKLIN A. STEARN.
